PRINTING PRESS FORMER

Curtis S. Crafts, Oak Park, Ill., assignor to The
Goss Printing Press Company, Chicago, Ill., a
corporation of Illinois

Application July 20, 1945, Serial No. 606,132

7 Claims. (Cl. 270—86)

1

The invention relates to folders for printing presses and more particularly to novel and useful mounting for the former which makes the first or longitudinal fold in the associated webs from a printing press.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation with parts in section of mechanism embodying the invention;

Fig. 2 is a rear elevation of the same mechanism;

Fig. 3 is a section taken on line 3—3 of Fig. 1; and

Fig. 4 is a section taken on line 4—4 of Fig. 1.

Objects of the invention are to provide an improved mounting for the web-folding former, said improvements relating specifically to means for varying the angular setting of the former for products of different thicknesses by slightly raising and lowering the former nose about an axis near the top of the former; said variations in former inclination being effected without substantial change in the relation between the top edge of the former and the guide roller normally mounted along and above said top edge. Other objects of the invention are to provide an exceedingly simple, adjustable former mounting which requires the minimum of adjusting action in order to effect the desired movements thereof; also to provide a very strong and rigid structure wherein the relatively great weight of the former assembly may be moved through minute adjusting angles and distances with the maximum of ease and the minimum of binding or constriction. The improved construction of the invention also facilitates ease of assembly of the former and its mounting.

Broadly described, the invention provides a pivotal mounting for the former adjacent its upper edge, so that angular movement may be imparted to the lower tip of the former about

2

said pivotal axis without substantially disturbing the spatial relationship between the upper edge of the former and the upper guide roller. This pivotal mounting is exceedingly simple in construction comprising merely a hinge on a shaft, the axis of the hinge being located to the rear and slightly below the level of the axis of the upper roller, so that the plane passing through the axes of said hinge and roller intersects the projected plane of the face of the former at the surface of the roller; that is the projected plane of the former is tangent to the surface of the roller substantially at the line of intersection of said axis-connecting plane. This construction permits angular adjustment of the former tip without substantially changing the spatial relation between the surface of the roller and the upper edge of the former. Relatively simple means are provided for imparting the angular adjusting movement to the tip of the former. Means are also provided for adjusting the former up and down in its own plane without disturbing the other elements of the mounting.

It will be understood that the foregoing general description and the following detailed description as well are exemplary and explanatory but are not restrictive of the invention.

Referring now in detail to the present preferred embodiment of the invention, illustrated by way of example in the accompanying drawings, the former 10 and its associated parts are mounted on and supported from a main bracket 11 which is triangular in side elevation and rectangular in plan. At its upper edge, a cleat 12 is bolted so that its flange overlies and is guided by the projecting lip 13 of the upper folder cross-brace 14.

The former 10 comprises a triangular plate of generally conventional form, having a downwardly tapered and angled nose 20 and horizontal upper edge or base 21 from which projects a tapered, edge-forming blade 22. Said former plate is mounted, by means hereinafter described in detail, upon a former-supporting bracket 25. Said bracket is of open triangular construction and designed to lie behind the former 10 and for the most part in a plane parallel therewith.

In accordance with the invention means are provided for supporting the former bracket 25 for hinged movement about a horizontal axis at the upper end of said bracket. For this purpose the bracket 25 is provided with rearwardly and upwardly curved yoke arms 26 which at their ends are provided with bushings 27 journaled

about either end of horizontally-disposed shaft 28. Said shaft is supported in brackets 29 formed along the top of the main bracket 11. The former-supporting bracket 25 is thus free to turn about fixed shaft 28. The upper web guide roller 30, which lies parallel with and almost in contact with the upper edge of the blade 22, is thus positioned between the shaft 28 and the blade 22. In accordance with the invention, it is desirable that the edge of blade 22 be maintained in said close spatial relation to the periphery of the roller 30 throughout any angular movement which may be imparted to the former for adjustments of the nose end 20 thereof. Bearing in mind that the upper edge of blade 22 of the former will travel in a circular arc A described about the axis of shaft 28 as a center, the positioning of said shaft and the center of roller 30 is such that the center line of shaft 28 preferably lies on a line parallel to the center line of roller 30 and in or substantially near to a plane B passing through said center lines of roller 30 and the line of tangency of the former face 10 on the opposite peripheral surface of the roller 30. By virtue of this construction it is possible to maintain relatively the same clearance between the surface of the roller 30 and the edge of blade 22 at the top of the former throughout all adjustments made at the nose 20 to compensate for various thicknesses of products run over the former.

Referring now to the mounting of the former on the supporting parallel bracket 25, means are provided for adjusting the former up and down within the inclined plane in which it is normally held. For this purpose the upper part of the rear face of the former is provided with two parallel spaced apart keys 36 projecting therefrom and disposed to ride in suitable ways provided in the adjacent face of the bracket 25. Similarly key 37 is provided centrally of the former near the lower portion thereof to fit within keyway slot 38 in the bracket 25. Two sets of locking screws 35 in the upper portion of the former and locking screws 38 near the lower portion are provided for fastening the bracket to the former when the desired longitudinal positioning thereof has been attained by movement of the former with respect to the bracket. By loosening the screws 38 and 35, the former may be slid up and down on the bracket 25 to provide the desired clearance of the blade 22 with respect to the roller 30. This up-and-down adjusting movement is preferably effected by screw 40 threaded into the keyway supporting structure.

The invention provides means for imparting angular movement to the nose end of the former 20 for the purpose described. This means comprises a rod 50, one end of which is pivotally connected by cross-shaft 51 to the bottom of the bracket 25. The rod extends rearwardly from said pivotal connection to a pivotal support on the bracket 11 adjacent the rear face thereof, said support being formed on a cross-shaft 55 which is journaled in brackets 56 extending rearwardly from said bracket 11. The shaft 55 is provided with an enlarged central portion 52 which houses a transversely-disposed sleeve 57 surrounding rod 50, the inner end of which sleeve is tightened against shaft 55 by a threaded portion 58 and nut 59. The outer end of said sleeve 57 is enlarged and internally threaded at 60 to engage the threads 61 formed on the outer end portion of the rod 50. A hand-wheel 62 is pro-

vided for turning said sleeve, thereby to effect axial movement of the rod 50 to adjust the position of the nose of the former 20 as will be clear. Stationary stop pin 65 is set to project from the rear face of housing 52, while cooperating stop pin 66 projects inwardly from the forward face of sleeve 72, said pins being preferably provided to prevent more than a full revolution on the part of the hand-wheel 62, thus providing for complete adjustment in either direction from the zero or normal angle position of the former by a half turn of the handwheel in either direction. An indicator pointer 78 may be formed on the shaft 55, cooperating with a marked dial 71 on the flange of the sleeve 72, fixed to the sleeve 57 by set screw 63.

The invention in its broader aspects is not limited to the specific mechanisms shown and described but departures may be made therefrom within the scope of the accompanying claims without departing from the principles of the invention and without sacrificing its chief advantages.

What is claimed is:

1. A mounting for a printing press former, including in combination, a triangular former plate mounted in an inclined plane, a horizontal roller adjacent the upper edge of said plate, a bracket for supporting said plate in said plane, the bracket being mounted for angular movement about a horizontal axis, and means for varying the positions of the former plate with respect to said bracket in said inclined plane.
2. A mounting for a printing press former, including in combination, a triangular former plate mounted in an inclined plane, a horizontal roller adjacent the upper edge of said plate, a bracket for supporting said plate in said plane, the bracket being mounted for angular movement about a horizontal axis, means for varying the positions of the former plate with respect to said bracket in said inclined plane, and means for varying the inclination of the plate and bracket about said axis.
3. A mounting for a printing press former, including in combination, a triangular former plate mounted in an inclined plane, a horizontal roller adjacent the upper edge of said plate, a bracket for supporting said plate in said plane, the bracket being mounted for angular movement about a horizontal axis, said axis being behind the roller and above the bottom thereof, and means for varying the positions of the former plate with respect to said bracket in said inclined plane.
4. A mounting for a printing press former, including in combination, a triangular former plate mounted in an inclined plane, a horizontal roller adjacent the upper edge of said plate, a bracket for supporting said plate in said plane, and means for varying the positions of the former plate with respect to said bracket in said inclined plane.
5. A mounting for a printing press former, including in combination, a triangular former, a roller adjacent the top edge of said former and a bracket supporting the former for pivotal motion about an axis parallel to that of said roller, the center line of the roller being between the upper edge of the former and said pivotal axis, and means for moving the former in its plane of inclination toward and away from said roller.
6. A mounting for a printing press former, including in combination, a triangular former plate mounted in an inclined plane with its apex lowermost, a support for so mounting said plate and

means for moving the former up and down in its plane of inclination on said support.

7. A mounting for a printing press former, including in combination, a triangular former plate mounted in an inclined plane with its apex lowermost, a support for so mounting said plate means for moving the former up and down in its plane of inclination on said support, and means for varying said plane of inclination of the former.
